APPARATUS FOR PREVENTING ACCIDENTAL DISCONNECTION OF PRESSURE SOURCES FROM WELL TOOLS

Harold J. Urbanosky, Houston, Tex., assignor to Schlumberger Technology Corporation, Houston, Tex., a corporation of Texas

Filed Oct. 14, 1966, Ser. No. 586,806
8 Claims. (Cl. 285—83)

ABSTRACT OF THE DISCLOSURE

A pressure-responsive latching means for preventing premature disconnection of multi-sectional well tools containing high-pressure fluids. A piston or other member is urged by fluid pressure within the well tool into latching engagement with stop means on the coupling means to prevent their premature disconnection before the entrapped high-pressure fluid has been safely removed or vented.

This invention relates to well tools; and, more particularly, this invention pertains to new and improved pressure-responsive latching means for preventing premature disconnection of multi-sectional well tools still containing high-pressure fluids.

The present trends toward smaller diameter well bores as well as more elaborate well-completion operations have made it necessary to make well tools substantially longer than heretofore. As a result, many well tools are of such length today that they must be made in separable sections of a convenient size that can be taken separately to the well and coupled there before being used. Obviously, these sections must also be disconnected before leaving the well.

It will be appreciated that coupling and uncoupling of such multi-sectional well tools must be done as quickly as possible to minimize the time that other well operations are halted. As a matter of expediency, therefore, a multi-sectional well tool will often be progressively "broken down" as quickly as possible during the course of its removal from the well bore to facilitate further handling of its several sections. Ordinarily this procedure poses no particular problem and is quite acceptable.

Many well tools commonly in use today, however, sealingly enclose high-pressure fluids such as, for example, either fluid samples from the well bore and earth formations or gases released by various combustibles sometimes used to actuate pistons or certain setting tools. It will be appreciated, therefore, that an accidental unconfined discharge of such high-pressure fluids presents a definite hazard to equipment and nearby personnel. Although this hazard is recognized by all, in the haste of quickly uncoupling a multi-sectional well tool to further speed operations, it is not at all unlikely that it could be inadvertently uncoupled at a connecting joint where the high-pressure fluids would suddenly escape and do considerable damage. Inasmuch as a well tool is generally coated with mud and the like as it is being retrieved from a well bore, it is, of course, impractical to rely only upon warning labels or the like to prevent such accidents.

Accordingly, it is an object of the present invention to provide new and improved means for preventing the inadvertent uncoupling of those connections in multi-sectional well tools from which high-pressure fluids could unexpectedly escape. This and other objects of the present invention are provided by arranging pressure-responsive latching means, such as a piston member in a bore, between a potential source of high-pressure fluids and the section-coupling means. In this manner, should there still be high-pressure fluids confined in a portion of the

well tool about to be disconnected, the piston, or another member aligned therewith, will be urged by the pressure differential into latching engagement with stop means on the coupling means and prevent their premature disconnection before the entrapped high-pressure fluid has been safely removed or vented.

The novel features of the present invention are set forth with particularity in the appended claims. The operation together with further objects and advantages thereof, may best be understood by way of illustration and example of a certain embodiment when taken in conjunction with the accompanying drawings, in which:

FIG. 1 shows a multi-sectional well tool such as might employ the present invention;

FIG. 2 is a simplified, schematic representation of one section of the apparatus depicted in FIG. 1;

FIG. 3 is a cross-sectional elevational view of a portion of the apparatus shown in FIG. 1 and depicting a preferred embodiment of the pressure-responsive latching means of the present invention; and

FIG. 4 is a cross-sectional view taken along the lines 4-4 in FIG. 3.

As will subsequently become apparent, it will be understood that the present invention has utility with any multi-sectional well tool having the capability of either accidentally or purposely entrapping a fluid under high pressure. Accordingly, although the present invention is described in conjunction with the particular multi-sectional tool 10 shown in the drawings, this tool represents only a typical example of how the latching means of the present invention may be best employed. It will be understood, therefore, that the pressure-responsive latching means of the present invention can be used to equal advantage with other multi-sectional well tools of even a totally dissimilar nature. Inasmuch as the fluid-sampling tool 10 is fully described in copending applications Ser. No. 557,108, filed June 13, 1966, by Frank R. Whitten and Ser. No. 583,778, filed Oct. 3, 1966, by Harold J. Urbanosky, and the details of its operation play no particular significance in understanding the present invention, only a brief description of these and other details of this well tool is believed necessary to illustrate the usefulness of the present invention in a typical application.

Turning now to FIG. 1, the multi-sectional fluid-sampling apparatus 10 is shown suspended from a multi-conductor cable 11 in a borehole 12 and in position there adjacent to a formation interval 13 for collecting a sample of producible fluids therefrom. The cable 11 is spooled in the usual manner from a winch (not shown) at the earth's surface, with some of its conductors being arranged there for selective connection to a power source and typical indicating-and-recording apparatus. The fluid-sampling apparatus 10 is comprised of a plurality of tandemly arranged, self-contained testing tools 14 that are each capable of independent operation to take a fluid sample. As seen in FIG. 1, each of these tools 14 have extendible sample-admitting means 15 that are longitudinally aligned along one side of the sample apparatus 10 and arranged for selective extension into sealing engagement with the exposed face of the earth formations such as at 13, for obtaining samples of formation fluids.

As best seen in FIG. 12, in addition to the sample-admitting means 15, each testing tool 14 further includes sample-collecting means 16 for recovering the fluid samples, and retracting means 17 for restoring the sample-admitting means to their initial position. These pressure-responsive means 15-17 are independently controlled by selectively operable valves 18-21 which, in response to electrical signals from the surface, are opened in a particular sequence to admit borehole fluids to these pressure-responsive means as their source of motivating power.

Briefly, the sample-admitting means 15 include an annular, elastomeric sealing member 22 mounted on the outer end of a slidable tubular member 23 that is fluidly sealed within the tool 14. A slidable tubular piston member 24 coaxially mounted around the smaller tubular member 23 will urge the sealing member 22 into sealing engagement with the earth formations whenever well control fluids are admitted through a branched passage 25 into an enclosed space 26 behind the piston by opening the valve 20. The rear of the tool 14 will, of course, at that time be engaged against the opposite borehole wall. An encapsulated shaped charge 27 that is selectively detonatable from the surface is mounted in the forward end of the tubular member 23 for use as required to provide increased fluid communication with earth formations.

The sample-collecting means 16 includes fluid-receiving compartments 28 and 29 separated from one another by a flow restrictor 30. A water cushion 31 is disposed in one compartment 28 and isolated therein a floating piston 32. Since the other compartment 29 is initially empty, formation fluids (at whatever the formation pressure is) will enter the compartment 28 and move the piston 32 at a rate regulated by the discharge of the water cushion 31 through the orifice 30 and into the other compartment.

To conduit a fluid sample from the sample-admitting means 15 to the receiver, the sample-collecting means 16 also include fluid passage means, such as a series of interconnecting passages 33-35 between the sample-admitting means and the compartment 28. A normally-closed, piston-operated valve 36 is serially arranged with a normally-open, piston-operated valve 37 to control fluid communication through the fluid passages 33-35. The so-called "flow-line" valve 36 prevents entry of well control fluids through the tubular member 23 and into the sample-receiving compartment 28 as the apparatus 10 is being positioned. This flow-line valve 36 is controlled by selectively operable valve 19 which, when opened, admits well control fluids through an associated passage 38 into an annular piston space 39. The so-called "seal" valve 37 is arranged to close-off the sample compartment 28 once a fluid sample is collected by opening the control valve 18 to admit well control fluids through a passage 40 into an enclosed piston space 41.

In general, the retracting means 17 are comprised of one or more pistons 42 arranged to develop a hydraulic pressure in a piston chamber 43 that is greater than the hydrostatic pressure of the well control fluids. An outlet passage 44 from the chamber 43 is controlled by a normally-closed, piston-actuated valve 45 that is itself controlled by the control valve 21. An extendible piston member 46 with an easily broken, weakened forward end 47 is also provided to admit well control fluids into the tool 14 should the hydraulic system fail.

In one manner of operating the tool 14, the apparatus 10 is positioned as shown in FIG. 1 opposite the formation 13. Then, the control valve 20 is opened to simultaneously extend the piston 24 and the extendible member 46 on the opposite side of the testing tool 14 and parallel to the piston 24. The flow-line valve 36 must, of course, be opened to admit fluid samples into the sample-collecting compartment 28 once the sealing member 22 is sealingly engaged with one wall of the borehole. Should it be necessary, the shaped charge 27 is then detonated to provide further fluid communication into the formation 13.

To retrieve the apparatus 10, the control valve 18 is first opened to close the seal valve 37 and trap whatever fluids there may be in the sample-collecting compartment 28. The control valve 21 is then opened to in turn open the normally-closed hydraulic valve 45 and admit the hydraulic fluid into previously closed spaces 48 and 49 in front of the piston member 24. Since the hydraulic pressure is greater than the hydrostatic pressure of the well control fluids in the piston space 26, as the hydraulic fluid enters these previously closed spaces 48 and 49, the piston

24 and the extendible member 46 will be returned to their initial positions. A piston-actuated equalizing valve 50 is so arranged that when the hydraulic valve 45 is opened, the equalizing valve will be opened by the hydraulic fluid to admit well control fluids into the extendible tubular member 23 to prevent the differential between the hydrostatic and formation pressures from holding the sealing member 22 against the formation 13 when it is desired to retract it.

10 It will be appreciated, therefore, that whenever the apparatus 10 is retrieved from the well bore, each of the sample-receiving chambers 28 in the tools 14 will supposedly contain a high-pressure fluid whether this be a formation fluid sample or is merely the control fluid or "mud" in the well bore at the depth and pressure where the sample-admitting means 15 were employed. As previously mentioned, the pressure of these entrapped fluids must be safely relieved to prevent their accidental discharge.

20 As best seen in FIG. 1, to keep the apparatus 10 with-in manageable proportions, it is preferred to combine two sample-admitting means 15 of two adjacent tools 14 and their associated valves into a single integral body, as at 51, and to enclose their respectively associated sample-collecting means 16 in separate housings, as at 52 and 53, that are tandemly connected at the opposite ends of the integral body. Appropriately arranged interconnectors and 55 (such as more fully described in the aforementioned copending Urbanosky application) are respectively 25 used to couple the adjacent free ends of the housings 52 and 53 to still others of the tools 14 and to couple these 30 housings to the opposite ends of the body 51.

35 Accordingly, the upper end of one of the interconnectors 55 is shown in FIG. 3, as it will appear as it is being coupled to the adjacent lower end of its associated sample-admitting section 51. The lower end of the interconnector 55 has already been connected to the housing 52 as explained in greater detail in the aforementioned copending Urbanosky application. To accommodate various electrical conductors 56 running to the other tools 40 therebelow, a tubular conduit 57 is extended through the fluid compartments 28 and 29 along the central axis of the sample-collecting section 52 and fluidly sealed, as by 45 O-rings 58, at each end. The floating isolating piston 32 (not seen in FIG. 3) must, of course, be made annular and is fluidly sealed around the tubular conduit 57 by O-rings (not shown).

50 A fluid connection must also be provided between the sample-admitting section 51 and the sample-collecting section 52 that corresponds to the passage 35 (FIG. 2) beyond the seal valve 37. Therefore, as seen in FIG. 3, to make this fluid connection, a longitudinally projecting tubular member 59 is secured to the sample-admitting section 51 and adapted for reception in a complementary longitudinal bore 60 in the upper end of the interconnector 55. O-rings 61 around the free end of the tubular extension 59 complete the fluid-tight connection.

55 To mechanically couple the interconnector 55 to the sample-admitting section 51, the lower end of the sample-admitting section is counterbored, as at 62, and adapted to receive the adjacent reduced-diameter end 63 of the interconnector. Selectively operable connecting means 64 are provided such as an externally threaded ring or collar 65 that is loosely mounted around the reduced end 63 of the interconnector 55 and adapted for threaded engagement with internal threads 66 within the counterbore 62 in the sample-admitting section 51. A shoulder 67 on the interconnector 55 and a split-ring 68 respectively immediately below and above the loose collar 65 confine the collar against significant longitudinal movement.

60 Once the tubular extension 59 is oriented with its associated bore 60, the sections 51 and 52 (with the interconnector 55 already thereon) are brought together so the collar 65 can be threaded engaged with the threads 66 and tightened upon further rotation of the collar. As

the collar 65 is tightened, the sections 51 and 52 will be pulled still closer together and the tubular extension 59 will be inserted into its respective bore 60. The sections 51 and 52 and interconnector 55, of course, do not rotate as the collar 65 is being rotated. An O-ring 69 around the extremity of the end portion 63 fluidly seals the sample-admitting section 51 relative to the interconnector 55 whenever the two members are finally coupled.

Once the tubular member 59 is partially in its receptive bore 60, electrical interconnection between the two sections 51 and 52 is accomplished by opposed, axially aligned, multi-contact mating connector members 70 and 71 respectively mounted in the adjacent ends of the section 51 and interconnector 55. As fully explained in the aforementioned Urbanosky application, one of the connector members 70 is capable of limited rotation and longitudinal movement and the other connector member 71 is secured against both rotational and longitudinal movement. In this manner, as the two adjacent ends of the section 51 and interconnector 55 are brought together into the position shown in FIG. 3 by the threaded collar 65, the movable connector 70 is appropriately oriented relative to the fixed connector 71 by means of a cooperatively arranged key 72 and longitudinal slot 73 in tubular members 74 and 75 supporting the connectors so as to permit their accurate interconnection.

It will be appreciated, of course, that whatever fluids are entrapped in the sample-collecting section 52 will usually be at a substantial pressure. After the apparatus 10 has been returned to the surface, the entrapped fluids are supposedly removed through appropriately arranged ports (not shown) in each sample-collecting section, as at 52, by means of suitable high-pressure manifolds and containers (not shown). As already discussed, however, it is quite possible that the connection as, for example, at 64 between the sections 51 and 52 could be inadvertently disconnected before the high-pressure fluids have been removed.

Accordingly, as seen in FIGS. 3 and 4, in accordance with the present invention, premature disconnection of the sections 51 and 52 is prevented by providing pressure-responsive latching means, such as a lateral bore 76 located to at least partially intersect the bore 60 and a piston 77 slidably disposed and fluidly sealed therein, that are adapted for latching cooperation with the connecting means 64. To accomplish this cooperation, the outer opening of the lateral bore 76 is located immediately below at least a portion of the internal circumferential surface 78 of the collar 65. This internal surface 78 of the collar 65 is appropriately recessed, as at 79, to provide an inclined surface portion 80 (FIG. 4) that is gradually tapered outwardly and in the direction of rotation for threading the collar onto the threads 66 and then intersected by stop means, such as a substantially radial surface portion 81 in the recess.

Thus, should there still be pressure in the sample chamber 28 and bore 60, the outer end 82 of the piston 77 will be urged outwardly against the internal circumferential surface 78 of the threaded collar 65. It will be appreciated, therefore, that rotation of the collar 65 through no more than one full turn in the direction to unthread it will bring the recess 79 over the extended piston end 82. Then, since the pressure differential will force the outer end 82 of the piston 77 further outwardly and into the recess 79, continued rotation of the collar 65 in that direction will be positively halted whenever the outer piston end moves into latching engagement with the radial end surface 81 of the recess. Once, however, all pressure has been relieved from the compartment 28, the collar 65 can, of course, be retightened sufficiently for the camming action of the inclined surface 80 of the recess 79 against the outer piston end 82 to restore the piston 77 to its retracted position. The collar 65 can then be returned in the opposite direction to continue disconnecting it from the threads 66. It will be realized,

of course, that a separate member (not shown) could be slidably disposed in the bore 76 and so arranged that its outer end is instead urged into the recess 79 by the piston 77.

It will be appreciated, therefore, that the cooperative latching action of the piston 77 with the surfaces 80 and 81 in the recess 79 in the collar 65 will prevent the premature disconnection of a fluid-containing well tool whenever this fluid is at a pressure greater than that exterior of the tool. Moreover, it should also be repeated that although the present invention has been described as having particular utility with sample-collecting tools, other typical well tools such as setting tools, tight-hole testers, and the like, will be equally improved by the present invention. In this manner, pressure-responsive latching means arranged in accordance with the principles of the present invention will enable multi-sectional well tools to be disconnected without fear that one section will be disconnected at a point whereby high-pressure fluids could suddenly escape unchecked and without warning.

While a particular embodiment of the present invention has been shown and described, it is apparent that changes and modifications may be made without departing from this invention in its broader aspects; and, therefore, the aim in the appended claims is to cover all such changes and modifications as fall within the true spirit and scope of this invention.

What is claimed is:

1. In a well tool having first and second separable bodies with adjacent ends adapted for interconnection with one another, first fluid-passage means extending from within said first body to its said adjacent end, second fluid-passage means extending from within said second body to its said adjacent end, and a chamber adapted to contain a high-pressure fluid in said tool and connected to one of said fluid-passage means, the improvement comprising: first means for releasably interconnecting and sealing said fluid-passage means including a tubular member connected to said first fluid-passage means and projecting from said first body end, a complementary bore in said second body end connected to said second fluid-passage means and adapted to receive said tubular member and first sealing means adapted for sealing said tubular member in said bore; second means for releasably interconnecting and sealing said adjacent body ends including a threaded ring rotatably mounted around one of said body ends and adapted for threaded engagement with the other of said body ends, and second sealing means adapted for sealing said body ends to one another; and means responsive to a pressure differential between said fluid chamber and the exterior of said tool for preventing disconnection of said interconnecting means including a second bore communicating one of said fluid-passage means with the exterior of said tool, piston means sealingly received in said second bore and movable therein by such a pressure differential, and latching means responsive to movement of said piston means for preventing rotation of said threaded ring from threaded engagement with said other body end.

2. The well tool of claim 1 wherein said latching means include stop means on said threaded ring and means movable by said piston means into latching engagement with said stop means.

3. The well tool of claim 1 further including camming means on said threaded ring for disengaging said latching means upon rotation of said threaded ring into further threaded engagement with said other body end whenever there is no pressure differential between said fluid chamber and said tool exterior.

4. The well tool of claim 3 wherein said latching means include said stop means on said threaded ring and means movable by said piston means into latching engagement with said stop means.

5. The well tool of claim 1 wherein said second bore is in said one body end and is terminated in an opening

adjacent to said threaded ring; said piston means include a rigid member with an outer end movable from a position within said second bore to a position partially extending from its said opening; and said latching means include stop means on said threaded ring adapted to engage said outer end of said rigid member whenever said outer end of said rigid member is partially extended from said bore opening and prevent its further rotation of said ring from threaded engagement with said other body end.

6. The well tool of claim 5 wherein said stop means include a recess in said threaded ring adapted to receive said outer end of said rigid member and having an end surface adapted for engagement with said partially-extended outer end of said rigid member whenever said threaded ring is rotated from threaded engagement with said other body end.

7. The well tool of claim 6 further including a surface in said recess inclined outwardly and in the direction of rotation for unthreading said threaded ring whereby rotation of said threaded ring into further threaded engagement with said other body end will cam said outer end of said rigid member back into said second bore whenever there is no pressure differential between said fluid chamber and said tool exterior.

8. In a well tool having first and second separable bodies with adjacent ends, a pressure chamber in one of said bodies, and passage means extending from said pressure chamber through said body ends to the other of said bodies, the improvement comprising: means for releasably interconnecting said adjacent body ends including a threaded ring rotatably mounted around one of said body ends and adapted for threaded engagement with the other

10
15

of said body ends, and stop means on said threaded ring; means movable into latching engagement with said stop means in response to a pressure differential between said pressure chamber and the exterior of said tool for preventing unthreading of said threaded ring upon rotation of said threaded ring away from threaded engagement with said other body end; and camming means on said threaded ring for disengaging said movable means from said stop means upon rotation of said threaded ring into further threaded engagement with said other body end whenever there is no pressure differential between said pressure chamber and said tool exterior.
